UNITED STATES PATENT OFFICE.

EDWARD DREFS, OF MILWAUKEE, OREGON.

FOLDING BED.

1,400,734.

Specification of Letters Patent. Patented Dec. 20, 1921.

Application filed December 9, 1919. Serial No. 343,675.

To all whom it may concern:

Be it known that I, EDWARD DREFS, a citizen of the United States, residing at Milwaukee, in the county of Clackamas and 5 State of Oregon, have invented certain new and useful Improvements in a Folding Bed, of which the following is a specification.

For touring purposes it is desirable to provide a bed which may be reduced to a 10 compact form for convenience of handling and stored so as to occupy a relatively small space, whereby it may be readily carried as an accessory and which may be quickly set up for use and easily folded to a relatively 15 small bundle so as not to occupy a great amount of space thereby adapting it to be carried in the car or other vehicle.

While the invention provides a bed primarily intended for outdoor use when camping, the construction is such that the bed 20 may be used indoors or wherever desired, the novelty residing in the structure, permitting the bed to be folded and unfolded. When set up for use, the bed is capable of 25 sustaining ordinary use. As a whole, the invention is simple, light, durable and lasting and may be easily handled by the average person and set up and reduced to compact form without the use of tools.

30 The drawings illustrate a preferred embodiment of my invention. However, it is to be understood that in adapting the same to meet different conditions, various changes in the form, proportion and minor details of 35 construction may be resorted to without departing from the nature of the invention as claimed hereinafter.

Referring to the drawings hereto attached—

40 Figure 1 is a top plan view of a folding bed embodying the invention showing the same set up for use,

Fig. 2 is a side view of the bed,

Fig. 3 is an end view, parts being broken 45 away and parts in section,

Fig. 4 is a view of the parts illustrated in Fig. 3 showing the same in folded position, and

50 Fig. 5 is a detail view of one of the stays. Corresponding and like parts are referred to in the following specification and indicated in the several views of the drawings by like reference characters.

The bed comprising a bottom 1, legs 2 and 55 stays, the latter being provided in sufficient number to hold the bed in adjusted posi-

tion when set up. As shown most clearly in Fig. 1 there will be four stays, one for each corner of the bed. The stays comprise a number of parts which are so constructed 60 as to enable the bed to be readily subjected to tension whereby the bottom is maintained in stretched condition at all times when the bed is properly set up.

The bed bottom 1 may be of any formation and as shown comprises a plurality of sections which are constructed in a manner to admit of the sections folding one upon the other so as to provide a small and compact bundle. The several sections are 70 connected by means of links 3 and as shown most clearly in Fig. 1, the sections are of like size and formation and the links are such as to admit of the sections folding one upon the other. Contractile helical springs 75 4 connect the bed bottom with end bars and are relied upon to yieldably support the bed bottom.

Each end bar comprises similar or like sections 5 and 6 which are hingedly connected as indicated at 7. A bar 8 is secured at one end to one of the sections and projects beyond the hinge point 7 so as to engage the other section to which it is made secure by means of a bolt or like fastening. 80 As shown most clearly in Fig. 3, the bar 8 is riveted or otherwise secured at one end to the section 5 and its projecting end is adapted to underlap the section 6 to which it is secured by means of the bolt 9. It will 90 thus be understood that the bar 8 extending across the hinged point 7 braces and strengthens the two sections 5 and 6 and holds them in extended position.

The legs 2 are of like formation, each being provided at its lower end with a foot 10 and having a lateral extension 11 at its upper end to engage the under side of the end bar so as to hold the leg in upright position. The leg 2 preferably consists of a bar which 100 has one end bent upon itself to form the foot 10 which is a triangular outline. The opposite end of the bar is bent laterally to form the extension 11. An eye at the upper end of the leg receives a pivot fastening 12 105 which may consist of a bolt or fastening of any form. A clamp 13 is secured to the terminal portion of each end bar and the upper end of the leg is preferably connected thereto by means of fastenings 12 which 110 extend through registering openings in the side members of the clamp and which

pass through the eye at the upper end of the leg. The legs are disposed so that the feet 10 and the lateral extensions 11 face outward thereby giving the best support.

- 5 Each of the stays comprise members 14, 15 and 16. The members 14 and 15 consist of bars of suitable length, whereas the member 16 consists of a rod or other suitable connection. The member 14 comprises companion elements which are spaced apart to receive an end of the bar 15. A link 17 connects the stay to a link 18 which is looped into an opening formed in the terminal portion of the end bar. A pin 19 connects the 10 outer ends of the companion bars comprising the member 14 and is adapted to engage one of a number of notches 20 formed in an edge of the member 15 whereby the length of the stay may be regulated. The notches 15 20 are enlarged or undercut at their inner ends so as to engage the pin or fastening 19 and prevent disengagement of the members 14 and 15 when adjusted. The ends of the member 15 are curved as shown most clearly 25 in Fig. 5 and the rod or member 16 is connected to the upper curved end of the member 15, whereas the opposite curved end of the member 15 terminates in a hook 21 which is adapted to engage the member 16 and hold 30 the parts comprising the stay in adjusted position. The outer or lower end of the member 16 is adapted to engage a peg 22 or other suitable anchoring element whereby the stay is made secure when the bed is set 35 up. When the bed is used in the open, the pegs 22 are driven into the ground but when the bed is set up indoors the anchoring elements 22 may consist of any suitable fastening means whereby the stays may be 40 securely fastened.
- When the bed is folded or reduced to compact form, the several sections comprising the bottom will fold one upon the other and the end bars will double upon themselves 45 so that the sections 5 and 6 and the legs occupy a position one upon the other as indicated most clearly in Fig. 4. The stays are likewise folded. When the bed is set up for use, the end bars are strengthened and braced 50 by the bars 8 in the manner herein set forth

and shown most clearly in Fig. 3. The pegs 22 are driven into the ground in proper position so that the outer ends of the stays may be engaged therewith. The member 15 is adapted to be drawn into the fastening 19 as indicated by the full and dotted lines in Fig. 5. The parts are so adjusted that when the hooked end of the member 15 is swung upward the parts will assume the position substantially as indicated by the dotted lines 60 in Fig. 5 and when the hooked end of the member 21 is pressed downward the stay will be shorter thereby subjecting the bed bottom to tension, and by engaging the hook 21 with the member 16 the stay is maintained in the required position thereby holding the bed bottom under tension. It will be understood that the construction is such as to admit of the bed being quickly set up and readily reduced to compact form so as to be 70 conveniently carried upon an automobile or other vehicle.

Having thus fully described my invention what I claim as new and desire to secure by Letters Patent, is:—

75 In a bed, the combination of a foldable bed bottom and foldable end bars, the latter comprising hingedly connected sections and bars extending across and bracing the hinged point, a leg pivotally secured to said 80 end bar near each end thereof, each leg having the pivotal end thereof provided with a substantially right angular extension for engagement with the underside of said end bar to hold the leg in an upright position, an 85 angular extending foot formed upon the lower end of each leg and extending in the same direction from the leg as the right angular extension above mentioned, and said angular extending foot provided with an 90 inclined brace that is secured at its top end to the said leg for keeping the foot from bending upwardly.

In testimony whereof I affix my signature in presence of two witnesses.

EDWARD DREFS.
